PRAYER BENCH

Warren D. Kennell, Rochester, N. Y.

Application July 28, 1955, Serial No. 37,176

Term of patent 14 years

(Cl. D15—8)

FIG. 1.

FIG. 3.

FIG. 2.

FIG. 4.

Fig. 1 is a front perspective view of a prayer bench embodying my new design;

Fig. 2 is a rear perspective view thereof;

Fig. 3 is a sectional view of the prayer bench taken on the line 3—3 in Fig. 1, and

Fig. 4 is a fragmentary sectional elevational view along the line 4—4 of Fig. 3.

I claim:

The ornamental design for a prayer bench, substantially as shown.
